UNITED STATES PATENT OFFICE.

FRANK A. DUNNING, OF BLUE ISLAND, ILLINOIS.

SEAL-LOCK.

SPECIFICATION forming part of Letters Patent No. 337,938, dated March 16, 1886.

Application filed December 23, 1884. Serial No. 151,054. (Model.)

To all whom it may concern:

Be it known that I, FRANK A. DUNNING, a citizen of the United States of America, residing at Blue Island, in the county of Cook and State of Illinois, have invented certain new and useful Improvements in Seal-Locks, of which the following is a specification, reference being had therein to the accompanying drawings.

10 This invention relates to certain improvements in seal-locks for freight-cars, the construction and operation of which are fully set forth and explained in the following specification and claims; and in order to enable others skilled in the art to make and use said invention, reference is had to the following described drawings, making a part of this specification, in which—

Figure 1 is a side view of a car-door and a portion of a car, showing the lock attached to the car to hold the door closed. Fig. 2 is a similar view of the opposite side of the car, showing the manner in which that door is held closed. Fig. 3 is a perspective view of the lock having its face-plate removed. Fig. 4 is a perspective view of the face-plate of the lock. Fig. 5 is a perspective view of a combined hook and key to be used in unlocking the lock. Fig. 6 is a horizontal longitudinal section of the lock, looking down from line 2, Fig. 1, to show the interior mechanism. Fig. 7 is a perspective view of a tumbler having a spiral flange extending nearly around it, it being a portion of the interior of the lock. Fig. 8 is a cross-section of the lock on line 3, Figs. 1, 3, 6, and also showing a section of a car to show how the latch-bolt of the lock engages with the car when holding the car-door locked. Fig. 9 is a cross-sectional view of the lock on line 4 of Figs. 1 and 3, showing a side view of the spirally-flanged tumbler. Fig. 10 is a perspective view of the mechanism by means of which the car-door on the opposite side of the car from the lock is held closed when the lock is in the position shown in Fig. 1; and Fig. 11 is a similar view to that of Fig. 9, showing the form of the tumbler varied somewhat by the use of a rear spring and an extending lug instead of the spiral flange. Fig. 12 is a face view of the seal-ticket as it

appears attached to its stub in a book, and Fig. 13 is a view of the rear side of the seal-ticket from that shown at 3 in Fig. 12.

In the drawings, J represents the body or frame of the lock, having a cover or face-plate, 55 J', and a rear covering-plate, J², all firmly held together by suitable screws passed from the back through the rear covering-plate, J², and the body or frame J and secured into the face-plate J'. 60

The lock is intended to be pivoted to the side and near the bottom of a car by means of a bolt, B', having only its head exposed in such manner as to rest against and behind the car-door D when locked, and to be turned 65 back and down far enough to permit the car-door to slide over it in opening when it is unlocked, and to accomplish this the rear or pivoted end of the body or frame and its plates terminate in downwardly-extending lugs or 70 ears, and are provided with a hole, B², for the reception of bolt B', Figs. 1, 3, 4.

Within a chamber of frame J is placed a lever, a, arranged to pass through an opening in a latch-bolt, B, and be fulcrumed at 75 its extreme end, and in the front end of the lock between a solid portion of frame J and the rear covering-plate, J², (see Figs. 3, 6, and 8,) while the opposite or movable end of said lever a terminates in an enlarged side portion, which is arranged to extend from the chamber of frame J and through an opening, a', in face-plate J', and present a surface on the same plane as that of the face-plate. (See Figs. 1, 3, 4, 6, 9.) 80

The opening through latch-bolt B, through which lever a passes, is sufficiently long to permit the said bolt to be pressed back within the lock when latching to lock the car-door without pressing against or moving lever a, as 90 the said bolt is held engaged with lever a from the opposite direction by means of conical coil-spring t, placed in a chamber immediately back of said bolt B, and held therein by face-plate J'. Immediately over the enlarged and movable portion of lever a, and placed on a stud, v, in the center of a circular chamber in frame J, is a spirally-flanged tumbler, R, having a square key-socket, K². (See Fig. 7.) 95

In the lever a, immediately under the tum- 100

bler R, is a channel, R', in size and form suitable for the engagement of the spiral flange of the said tumbler. In order to move that end of the lever *a* to withdraw the latch-bolt B, so it 5 may become disengaged and withdrawn from its hold in the notch on the side of the car, the said tumbler is rotated by means of a key, such as is shown in Fig. 5. The square end of the key is passed through a key-hole, K', of face-plate J', so that stud *v* of the lock will enter hole *v'* of said key, and so the square end or shank of the key will enter the square socket K² of the tumbler. The tumbler is formed with its flange cut away on the side 15 next the lever *a* when said lever is back in its normal position within the lock, for the purpose of permitting said lever to be moved without rotating the tumbler by placing the hooked end N of the key K into the notch E of lever *a* and pulling outward, which will withdraw the latch-bolt B in the same manner as when the tumbler R is rotated. When the tumbler R has been rotated a complete revolution, it has moved the lever *a* out to its fullest 25 extent, and has also again brought the plane or unflanged side of the tumbler next to the lever, which will release the lever and permit it to be returned by the action of spring *t*; or when the lever is pulled out by means of the hooked end of said key the action of said 30 spring will be the same to return it.

To the front of face-plate J' is pivotally attached a cap, P, by means of a stud or rivet, P', and may be held up in its proper position, 35 as shown in Fig. 1, by means of spring S bearing against its side. A pair of hooked lugs, H' H', of the cap are held up against and under the hooks of a pair of hooked lugs, H, of face-plate J', which, together with the pivot 40 P', thoroughly prevents the cap P from being pried off from the face-plate J'. (See Figs. 1, 4.)

Immediately back of cap P and in face-plate J' is a slight depression, F, for the reception of a seal-ticket made from paper, such 45 as shown at 3, Fig. 12, which is placed therein by removing the cap P from over said depression when the lock is open or thrown back from off the plate c'.

50 When the lock is locked, the cap P rests on the plate c', and cannot then be removed from over the depression F to permit the ticket either to be inserted or removed.

A glass front, G, is placed in cap P, so the 55 seal-ticket may be inspected when the cap P is closed. An opening through face-plate J', immediately back of the center of the seal-ticket, communicates with the chamber in frame J, where lever *a* is located, and a punch 60 or prod, P², integral with said lever, immediately back of the opening behind said seal-ticket, will, when said lever is moved toward said ticket, pass through the opening in face-plate J' and perforates said seal-ticket so placed 65 in front of it, and thus indicate to an observer looking through glass G that the lock has been opened or tampered with.

When it is desired to attach the lock to a car, a shaft, S', having the attachments as shown in Fig. 10, is placed through the bottom 70 of the car under the floor, so the upper surface of plate c' of shaft S' will be on the same plane as that desired for the bottom of the lock, so when the lock is against the door, as shown in Fig. 1, it will rest upon the plate c', and a 75 flange, e, on the outer end of said shaft S' extends up to cover a portion of the lock, to prevent the lock from being pried off sidewise when locked. A thin metal plate, such as is shown at T in Fig. 1, is attached to the side of 80 the car, forming a guard to prevent the latch from wearing the car when the lock is being turned to open or close it.

It is intended that when the lock is closed 85 its bottom surface will rest on the bottom track, A, of door D, as well as on plate c' of shaft S'. To the opposite end of shaft S' from the lock, and to the opposite side of the car, is firmly secured a stop or check, S², arranged to stand against the lower corner of the door D' or 90 against the outer end of the bar D², secured to the bottom of said door, to hold the door closed, as shown in Fig. 2, when the lock is resting on plate c' of shaft S' in the position shown in Fig. 1; but when the lock is unlatched and 95 turned back off the plate c' and out of the way of door D, the shaft S' may then be rotated to turn the stop or check S², or pushed to one side out of the way, so door D' may be opened. The handle c² on said shaft furnishes means 100 to so operate said shaft. (See Figs. 1, 10.) It can thus be readily seen that when the door of a car is locked both doors must of necessity be locked, and that neither door can be opened without first pulling out lever *a* by 105 means of rotating said tumbler or by means of the hooked end of said key, as stated, to withdraw the latch-bolt from the side of the car, and that by so doing the seal-ticket will be perforated, and thus indicate that the lock 110 had been tampered with and the car-doors opened. These seal-tickets are printed to bear the number of stations, number of car, destination, &c., and be retained and filed away at the office at the terminus of the route for reference or any purpose for which they may be 115 useful.

The tumbler R may be formed, if desired, as shown in Fig. 11, which is as follows: To the front and upper part of the tumbler, and integral therewith, is a stud or lug, v², arranged to rest in a slot, v³, of the face-plate J', a spiral spring, t², holding the tumbler close to face-plate J', so the said lug v² may not become displaced. On the periphery of the said tumbler 125 is another stud or lug, R³. When the key K is inserted into the tumbler R, it is pushed back, which depresses spring t² and withdraws lug v² from hollow v³. The tumbler is then rotated one-half way around, which will bring 130 lug or stud R³ into channel R' of lever *a*, and by releasing the pressure on the key-spring t² will return the tumbler to the front of the lock, moving lever *a* with it, when lug v² will enter

another and lower slot, v^t , which will hold the lever a fast in that position; but in this case the lever a may be moved by the hooked end of the key without rotating the tumblers.

5 When the lock is turned back and off from plate c' of shaft S' , the said shaft may be moved endwise to move the stop or check S^t to one side of door D' on the opposite side of the car to move the stop or check S^t to one side of said 10 door to permit said door to be opened. In so doing the side of the car back of plate c' must be cut away for the entrance of said plate. If desired, the cap P , which covers the seal-ticket, may be hinged to open as a door, and arranged 15 to be held locked or closed by a spring-catch or catch-bolt on the interior, which may be constructed in various ways not necessary to be shown.

This lock has thus far been described as applied to a car; but it may be applied to any 20 door to hold it locked closed so it may not be opened without punching or perforating the seal-ticket.

Fig. 12 shows a face view of the seal-ticket 25 as it appears attached to its stub in a book, and Fig. 13 shows the rear side of the seal-ticket. It is intended, when the seal-ticket is placed in the lock, the agent will fill it up with the date and the number of the car, both on the 30 ticket and the stub which he retains. When the car arrives at its destination, the agent removes the seal-ticket from the lock, as de-

scribed, and fills it up on the back with the date of receipt, number of car, and his name, and then files it away for reference.

Having thus described my invention, what I claim as new, and desire to secure by Letters Patent, is as follows, to wit:

1. The seal-lock for cars shown and described, consisting of a pivoted frame having 40 side covering-plates, a spring latch-bolt having an elongated opening through its body, an interior lever having a ticket-perforating punch or prod and arranged to extend through the opening in the latch-bolt, a receptacle for 45 a seal-ticket covered by a transparent front cap, and the means described for operating said parts, substantially as and for the purpose set forth.

2. In the seal-lock shown and described, the 50 combination of the frame or case J , the lever a , having the prod P^t , the latch-bolt B , the spring t , and the tumbler R , as and for the purpose set forth.

3. In the seal-lock shown and described, the 55 combination, with the frame or case J , of the lever a , having the prod P^t , spring latch-bolt B , and the studded rotating tumbler R , all adapted to operate substantially as and for the purpose set forth.

FRANK A. DUNNING.
